ELECTRODE HOLDER FOR ARC LAMPS

Eugene R. Suttle, Wichita, Kans.

Application June 15, 1950, Serial No. 168,302

1. Claim. (Cl. 313—146)

1.

This invention relates generally to arc lamps, and more particularly to auxiliary electrode holders for such lamps—holders which will make possible the substantially complete use of partially burned electrodes which it has previously been necessary to discard.

As is well known to those familiar with this art, the two carbon electrodes in conventional arc lamps are mounted in axial alignment for movement toward each other as the burning tips disintegrate. To accomplish this, two opposing carriages are slidably mounted on a track or on guide bars, and the outer end of each electrode is held in a clamp which is a part of each carriage. The inner end of each electrode is supported by a stationary guide, the two guides serving to keep the burning ends of the electrodes aligned. The guides are located a short distance from the arc, and as the tips of the electrodes disintegrate, the moving carriages slide the electrodes through or along these guides. Some of these guides are V-shaped, some U-shaped, and some are of other cross-sectional shapes, depending on the choice of the manufacturer of the lamp.

Considering the amount of each electrode which is necessarily held in its clamp, the amount of each electrode which lies in its guide, and the required spacing of the arc from each guide, no electrode can be burned shorter than about 2½ inches with arc lamps presently available. With a negative electrode having an original length of 9 inches, this means that only approximately 72% of it is usable in the lamp.

When such arc lamps are used in commercial motion picture projecting machines, the electrode burning rate and the time required to project at least one double reel of film are two additional factors which enter into the problem. Since a standard negative electrode burns at the rate of about 2 inches in 20 minutes, and since the operator must have a continuous arc for about 20 minutes to run one reel of film, it is evident that the operator must have a negative electrode in his lamp at least 4½" long when he starts projecting a short feature or newsreel or he will be unable to run the roll of film continuously. Negative electrodes less than 4½ inches long are therefore discarded by projector operators. Disposing of a 4 inch used electrode which was only 9 inches long when new means a loss of approximately 45%, and a consequent increased cost for negative electrodes per year. A similar condition exists with relation to the slower burning positive electrodes.

2.

It is the chief object of this invention to provide arc lamp users with an auxiliary extension electrode holder which makes it possible for an arc lamp to burn both positive and negative electrodes until they are only 1 inch long, thus effecting a very material reduction in the total cost of electrodes.

It is an additional important object of the invention to provide an auxiliary electrode holder which will not cause mis-alignment of either electrode as the holder passes into and across the electrode guide, and which will freely pass through most, if not all, present electrode guides without changing the vertical or horizontal position of the electrode which it carries, and without the necessity of modifying the cross sectional shape of the guide.

The invention, together with other objects attending its production, will be more clearly understood when the following description is read in connection with the accompanying drawings, in which:

Fig. 1 is a side schematic view of the working parts of a standard arc projection lamp with the carbon electrodes shown in broken lines;

Fig. 2 is an inverted perspective view of a preferred form of electrode holder embodying this invention;

Figs. 3 and 4 are top and bottom views respectively of the holder;

Fig. 5 is a right side view of the holder mounted in a conventional clamp of an arc lamp assembly, the clamp being shown fragmentarily;

Fig. 6 is a left side view of the holder, the broken lines indicating the relative position occupied by an electrode when clamped in the holder;

Fig. 7 is an end view of the holder taken looking directly into the electrode clamping end;

Fig. 8 is a lateral section taken along the line 3—8 of Fig. 5;

Fig. 9 is a sectional view taken along the line 9—9 of Fig. 3, and illustrates the complementary shape of the butt end of a conventional electrode and the electrode holding socket in the holder; and

Figs. 10, 11, and 12 are end views of the holder operatively associated with three types of standard or conventional electrode guides; and

Fig. 13 is an end view of a different type of holder embodying the invention, operatively associated with a standard 90° guide.

The standard lamp assembly shown in Fig. 1 includes an independently supported track 15, a traveling negative electrode carriage 16, a nega-

tive electrode clamp 17 which is a part of and travels with the carriage 16, and a stationary negative electrode guide 18 which serves to support and position the burning end of the electrode during lamp operation. The assembly also includes a traveling positive electrode carriage 19, a positive electrode clamp 20 which is a part of and travels with the carriage 19, and a stationary but adjustable positive electrode guide 21 mounted on a supporting standard 22.

The two carriages 16 and 19 are suitably power driven, and are automatically moved slowly toward each other during operation of the lamp to compensate for the slow disintegration of the two electrodes at the arcing point. The electrodes 23 and 24 slide through the guides 18 and 21 respectively, as the carriages move toward each other. The speed of movement of the carriages is coordinated, each moving at a rate equivalent to the burning rate of its respective electrode. The guides 18 and 21 are ordinarily set from $2\frac{1}{2}$ to 3 inches apart, and the arcing takes place approximately midway between them during operation of the lamp. This spacing prevents arc heat from melting or otherwise damaging the guides, and necessitating their replacement. When either of the electrode clamps 17 or 20 approaches its respective electrode guide 18 or 21, the operator replaces the electrode at the first opportunity, to prevent interruption of his projection of a subsequent roll of film. The partially burned electrode is discarded.

After an electrode has been partially burned and replaced, the discarded portion may be placed in the holder of this invention and burned.

The embodiment of the invention illustrated in the drawing includes an elongated shank 25, which is preferably the same cross sectional size and shape as the electrode, and can thus be easily received and secured in the clamps 17 or 20. It also includes an integral electrode clamping head, designated as a whole by the numeral 26.

The head 26 is divided longitudinally by a saw cut into two cooperating electrode clamping jaws 27 and 28, both of which are integral with the shank 25, but are movable slightly toward each other due to the inherent resilience of the steel of which the holder is made. An elongated socket 29, of substantially the same cross sectional size and shape as the electrode to be held, is cut longitudinally into the free end of the head 26, part of the socket being formed in each of the jaws 27 and 28. The axis of the socket should coincide with the longitudinal axis of the shank 25. As shown in Fig. 9 the inner or blind end of the socket is shaped to receive the butt end of the electrode so that the corresponding surfaces of both the electrode and holder are substantially continuous.

The outer side surface 30 of the jaw 27 lies in a plane which is tangent to the cylindrical surface of the shank 25. The surface 31 of the jaw 28 also lies in a plane which is tangent to the surface of the shank 25, and the two surfaces 30 and 31 lie in planes which preferably intersect each other at an inclined angle of 60° , the reason for which will be herein explained.

The two jaws 27 and 28 are provided with aligned transverse holes to receive a clamping screw 32, as clearly shown in Fig. 8. The bored hole in the jaw 28 is slightly larger in diameter than the screw 32 and is smooth walled to permit the screw to turn freely therein. The hole in jaw 27 is threaded. Thus, when the screw is tightened, the two jaws 27 and 28 are drawn

toward each other, and exert a clamping force on that end of the electrode which is seated in the socket 29.

Figs. 10 to 12 inclusive illustrate the reason for forming the holder head 26 in the cross sectional shape described, with particular reference to the angle between the surfaces or faces 30 and 31. The purpose is to permit the holder to pass through electrode guides of varying cross sectional shapes without causing the electrode to mis-align either laterally or vertically with respect to the other electrode.

Fig. 10 shows the described holder passing through a guide 33 whose inside or electrode contacting surfaces diverge at an angle of 60° . It will be seen that if the shank 25 of this holder is properly oriented at the time it is inserted in either of the clamps 17 or 20, the surfaces 30 and 31 will contact and slide along the diverging inside surfaces of the guide 33 as the holder and its partially burned electrode are moved longitudinally by the carriage, and that the contact of the holder surfaces with the guide surfaces will not in any way affect the straight line travel of the electrode 23 clamped in the holder. This is true because the surfaces 30 and 31 of the holder are tangent to the surface of the electrode 23 as well as to the shank 25, and diverge at the same angle as the inside surfaces of this particular guide.

Fig. 11 illustrates the holder and its electrode 23 passing through what is commonly known as a 90° type guide 34. With this type guide the holder shank is oriented in the clamp 17 so that the surface 30 aligns with one inside surface of the guide. The partially burned electrode, the holder head 26, and the shank 25 may then pass through the guide without altering the straight line travel of the electrode, and without disturbing its alignment with its cooperating electrode.

Fig. 12 shows a guide 35 having a still different cross sectional configuration. When the holder is used with this type of guide, the holder shank 25 is oriented in the electrode clamp 20 to position the surface 30 in the same plane as the horizontal surface 36 of the guide. Thus as the lamp carriage moves the holder and its electrode 24 slowly toward the arcing point, the head 26 of the holder glides smoothly over the supporting surface of the guide without in any way disturbing the alignment of the burning electrodes.

Fig. 13 illustrates a slightly different embodiment of the invention associated with a 90° guide. It is identical in construction to the holder described, except for the cross sectional shape of the jaws 38 and 37, and the relative location of the electrode clamping socket in the head, both differences being clearly shown in this drawing figure. This type of holder works well in any 90° guide, but will not work in a 60° guide 33, or in a horizontal guide 35.

Having described the invention with sufficient clarity to enable those familiar with this art to construct and use it, I claim:

A holder for a conventional cylindrical electrode of an arc lamp comprising: a cylindrical shank of the same diameter as the electrode to be held; an enlarged integral head projecting longitudinally from one end of the shank and laterally to one side thereof only, the opposite side surfaces of the head adjacent the shank lying in intersecting planes tangent to the surface of the shank, the included angle of intersection of the two planes being between 28° and 130° ; a cylindrical electrode receiving socket in said head

of the same-diameter as said shank and extending to the end of the shank, the socket axis being aligned with the shank axis, and a portion of the socket between the lines of tangency of the opposite side surfaces of the head being open throughout the length of the socket; an axial slot in the head dividing it into two electrode clamping jaws; and means for forcibly moving said jaws toward each other to clamp an electrode in said socket, whereby an electrode seated in said socket 10 abutting the adjacent end of the shank has a socket exposed side surface forming a substantial continuation of the adjacent shank surface.
